UNITED STATES PATENT OFFICE.

GEORGE E. CRAIG AND JAMES W. McNABNAY, OF MUSKEGON, MICHIGAN, ASSIGNORS TO PARAGON RECOIL SNUBBER COMPANY, OF MUSKEGON, MICHIGAN, A CORPORATION OF MICHIGAN.

SHOCK ABSORBER.

Application filed October 24, 1921. Serial No. 509,910.

To all whom it may concern:

Be it known that we, GEORGE E. CRAIG and JAMES W. McNABNAY, citizens of the United States, residing at Muskegon, in the county of Muskegon and State of Michigan, have invented new and useful Improvements in Shock Absorbers, of which the following is a specification.

The object of this invention is to provide means for checking the recoil of the vehicle springs while permitting free compression movement of the springs.

Another object of the invention is to provide means for adjusting the frictional engagement between the parts so as to make the device adaptable for different loads.

A further object of the invention is to eliminate springs in the device excepting a small spring which connects the ends of the split ring together.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a fragmentary view showing the invention in use on an automobile.

Figure 2 is an enlarged view of the device itself.

Figure 3 is a sectional view.

Figure 4 is a view of the bar 14'.

Figure 5 is a view of the plate 6 which is provided with a key-hole shaped opening.

Figure 6 is a view of the split ring.

Figure 7 is a view of one of the discs 5.

Figure 8 is a view of the drum.

Figure 9 is a view of a key.

Figures 10 and 11 show modifications of the plate and belt respectively.

In these views 1 indicates a bracket which is adapted to be bolted or otherwise secured to a part of the chassis frame 2 of a motor or other vehicle. A bolt 3 is connected with this bracket and this bolt rotatably supports the drum 4 which is provided with recessed ends for receiving the friction discs 5 and the plates 6. The discs 5 may be made

from any suitable material such as brake band lining. One of the plates 6 is formed integral with the bracket or is suitably connected therewith so that it will not rotate and the other plate is suitably provided with an opening which engages a key 3' on the bolt so that this plate will not rotate, but I prefer to provide a square part 3* on the bolt for engaging a square hole formed in the plate 6', as shown in Figs. 10 and 11. A concave spring member 7 is placed on the bolt with its edges engaging the adjacent plate and this member is held on the bolt by the nut 8. By this means the frictional engagement of the plates with the discs can be adjusted. A split ring 9 surrounds the hub, the hub being preferably grooved to receive the ring and a lever 10 is pivoted to one end of the ring and a link 11 to the other end. The pivot pins 12 for said lever and link are perforated to receive the ends 75 of a spring 13 which acts to hold the split ring in expanded position. The outer end of the link 11 is pivoted to the central portion of lever 10 and a bar 14 is pivotally connected with the outer end of the lever, the 80 other end of the bar being connected to a part of the spring A of the vehicle.

It will thus be seen that upon the compression movement of the spring of the vehicle the split ring will simply revolve upon 85 the drum but upon the recoil of the spring the split ring will be contracted, due to the movement of the link and lever, so that the drum will be rotated and this movement of the drum will be resisted by the frictional 90 engagement of the parts.

Our improved device can be used with each spring of a vehicle or with only the rear as will be understood. Our device will work equally as well on a car that is heavily 95 loaded as it will on a car with a light load.

It is thought from the foregoing description that the advantages and novel features of the invention will be readily apparent.

We desire it to be understood that we may 100 make changes in the construction and in the combination and arrangement of the several parts, provided that such changes fall within the scope of the appended claims.

What we claim is:—

1. A shock absorber of the class described comprising a drum, frictional means for checking the rotation thereof, a split ring

- engaging the drum, members pivoted to the ends of the ring and with each other and means for connecting the members and drum with parts of a vehicle.
- 5 2. A shock absorber of the class described comprising a support adapted to be connected with a part of a vehicle, a drum rotatably mounted on said support, adjustable friction means for checking the rotation of
10 the drum, a split ring engaging the drum, members pivotally connected with the ends of the ring and with each other, means for connecting one member with a part of the vehicle and spring means for normally holding the split ring in expanded position.
- 15 3. A shock absorber of the class described comprising a bracket adapted to be connected with a part of a vehicle, a drum rotatably supported on said bracket, friction
20 means for checking the rotation of the drum, said means including frictional discs and non-rotatable plates engaging the same, a split ring on the drum, members pivotally connected with the ends of the ring and with each other and a bar connected with one member and adapted to be connected to a part of the vehicle.
4. A shock absorber of the class described comprising a bracket, a bolt carried thereby, a drum rotatably mounted on the bolt and having recessed ends, discs of frictional material located in said recesses, stationary plates engaging said discs, spring means for pressing the parts together, a split ring engaging the drum, a link and lever, each having one end pivoted to the ring and the link being pivotally connected with the center of the lever and a connecting bar pivotally connected with the free end of the lever and adapted to be connected with a part of a car.
- In testimony whereof we affix our signatures.

GEORGE E. CRAIG.
JAMES W. McNABNAY.
